UNITED STATES PATENT OFFICE.

ELLSWORTH E. FLORA, OF CHICAGO, ILLINOIS, ASSIGNOR TO THE SEAL & FASTENER CO., OF CHICAGO, ILLINOIS, A CORPORATION OF DELAWARE.

BARREL-HOOP.

1,130,078.

Specification of Letters Patent.

Patented Mar. 2, 1915.

Application filed January 31, 1914. Serial No. 815,806.

To all whom it may concern:

Be it known that I, ELLSWORTH E. FLORA, a citizen of the United States, residing at Chicago, in the county of Cook and State 5 of Illinois, have invented a new and useful Improvement in Barrel-Hoops, of which the following is a specification.

The primary object of my invention is to provide a construction of barrel-hoop where- 10 by it may be made, in any desired thickness for adequate strength, of thin metal-strap material. To accomplish this purpose I take thin metal strap of desired width and use a suitable length to form therewith a 15 hoop of two or more concentric layers, which I clench edgewise together, at intervals, thereby producing a practically solid hoop composed of a continuous length of the material.

20 In the accompanying drawing, Figure 1 is an edge view of a barrel-hoop of my improved construction; Fig. 2 is an enlarged edge view of a broken section of the hoop showing the joint formed by clenching together the ends of the concentric layers, and Fig. 3 is an inner face view of the same; Fig. 4 is a perspective view of a barrel provided with my improved hoops, and Fig. 5 is an enlarged section on line 5, Fig. 4.

25 The hoop 6 shown is formed of two layers or thicknesses of metal strap .023 in. thick and $\frac{3}{4}$ in. wide; though the dimensions of the strap or number of layers used may vary for different sizes of barrels 7 for which 30 the hoops are provided. These layers are clumped edgewise together at intervals to unite them into a practically solid hoop, the clumping being preferably performed in a manner that causes the joints 8 to present

35 inner projections 8^a, which, in driving the hoop into place upon a barrel, penetrate the wood and thereby secure the hoop in position, against loosening by displacement, without requiring any other fastening means 40 to that end. The joint shown is formed by the tool of my patent No. 1,038,109, dated September 10, 1912, though any other suitable means may be used for the clumping purpose.

45 50 The advantage of my improvement is due

not only to the cheapness and facility with which an adequately strong barrel-hoop, in every way fit for its purpose, may be produced, but it is particularly advantageous in enabling users to themselves manufacture 55 the hoops and not be required to wait for filling orders for them to hoop-makers. The latter manufacture barrel-hoops in different sizes for the trade on orders therefor, and it is not uncommon for the user to be kept 60 waiting several months for filling orders for special sizes. By my improvement, a user can provide himself with the necessary metal strap in reels, each carrying a continuous length of several hundred feet; and the ma- 65 terial may be readily taken, as needed, off a reel and hoop after hoop produced by cutting off the proper length of strap for each hoop to be formed, as described, of the de- 70 sired number of layers and clenching the layers edgewise together, thereby saving the delays referred to in having orders filled.

The hoop shown in the drawings is formed of only two concentric layers of the strap- 75 material, though when the ends of the latter overlap at a joint, as represented at 9, three thicknesses occur. This is preferable to maintaining two thicknesses throughout the hoop, which might be done, however, by leaving unfastened the inner end section of 80 the strap between the joint at 9 and that next adjacent on the right, to Fig. 1.

What I claim as new and desire to secure by Letters Patent is—

1. As a new article of manufacture, a 85 hoop formed of a single length of metal strap coiled into a plurality of concentric layers clenched edgewise rigidly together at intervals.

2. As a new article of manufacture, a 90 hoop formed of a continuous length of metal strap in a plurality of concentric layers clenched edgewise together at intervals to form joints presenting projections at the inner face of the hoop.

ELLSWORTH E. FLORA.
